United States Patent Office

Des. 233,052
Patented Oct. 1, 1974

233,052

GOLF STANCE INDICATOR AND CORRECTOR

Leslie Kenneth Napier Perryman, 6 Tonbridge Road,
Pembury, England

Filed July 18, 1972, Ser. No. 272,860

Term of patent 3½ years

Int. Cl. D21—02

U.S. Cl. D34—5 CB

Fig. 2.

FIG. 1 is a top perspective view of a golf stance indicator and corrector embodying my new design; and

FIG. 2 is a bottom plan view thereof.

I claim:

The ornamental design for a golf stance indicator and corrector, substantially as shown and described.
